UNITED STATES PATENT OFFICE.

MICHAEL L. MILBAUER, OF ROUNDUP, MONTANA.

NEEDLE.

Application filed December 2, 1922. Serial No. 604,544.

To all whom it may concern:

Be it known that I, MICHAEL L. MILBAUER, a citizen of the United States, residing at Roundup, in the county of Mussel-
5 shell and State of Montana, have invented new and useful Improvements in Needles, of which the following is a specification.

This invention relates to a needle, the general object of the invention being to 10 provide a device for threading laces through belts and the like.

This invention also consists in certain other features of construction and in the combination and arrangement of the several parts, to be hereinafter fully described, illustrated in the accompanying drawings and specifically pointed out in the appended 15 claim.

In describing my invention in detail, reference will be had to the accompanying drawings wherein like characters denote like or corresponding parts throughout the several views, and in which:—

Figure 1 is an elevation of the improved 20 needle.

Figures 2 and 3 are detail views of this needle.

As shown in these figures the needle 1 is of tapered shape and has an eye 2 at 25 its head for receiving the lacing or thread. Inclined slots 3 are formed in the walls of the needle and communicate with the

eye. A pin 4 extends through the eye and has its ends engaging the slots, the pin being provided with roughened parts, as 35 shown at 5. The lacing or thread 6 is passed into the eye and under the pin. The pin is then permitted to drop upon the thread or lacing so that when the same is stretched by a pull upon the needle the 40 tendency of the needle to pull away from the thread will cause the pin to have a wedge action upon the thread and thus clamp the same in the eye. As will be seen the head or rear part of the needle is 45 larger than the body or pointed part thereof and the head or rear part is also of greater diameter than the thread or lacing so that the needle will make a hole larger than the lacing or thread and thus the 50 lacing or thread will pass easily through the hole made by the needle.

What I claim is:

A needle of the class described having its rear part of greater dimensions than 55 the rest of the needle, said rear part having an opening therein for receiving a thread or lacing, means for holding the thread or lacing in the opening, such means consisting of a wedging bar and inclined 60 slots for receiving the ends of the bar.

In testimony whereof I affix my signature.

MICHAEL L. MILBAUER.
